(57) **CLAIM**

The ornamental design for a baseball tee as shown and described.

DESCRIPTION

FIG. 1 is a top, front right perspective view of a baseball tee, showing my new design;

FIG. 2 is bottom, rear left perspective view thereof;

FIG. 3 is a front view thereof;

FIG. 4 is a rear view thereof;

FIG. 5 is a left view thereof;

FIG. 6 is a right view thereof;

FIG. 7 is a top plan view thereof;

FIG. 8 is bottom plan view thereof;

FIG. 9 is a partial enlarged view of portion 9 in FIG. 1;

FIG. 10 is a partial enlarged view of portion 10 in FIG. 1;

FIG. 11 is a partial enlarged view of portion 11 in FIG. 2;

FIG. 12 is a partial enlarged view of portion 12 in FIG. 2; and,

FIG. 13 is a partial enlarged view of portion 13 in FIG. 2. The dash broken lines depict portions of the baseball tee. The dot-dash broken lines depict the bounds of the detail views. All broken lines form no part of the claimed design.

1 Claim, 13 Drawing Sheets
